UNITED STATES PATENT OFFICE.

FRANK C. H. STRASBURGER, OF CHICAGO, ILLINOIS, ASSIGNOR TO THE BOTTLEERS MACHINERY MANUFACTURING COMPANY, OF CHICAGO, ILLINOIS, A CORPORATION OF ILLINOIS.

BOTTLE-WASHING MACHINE.

1,200,999.

Specification of Letters Patent.

Patented Oct. 10, 1916.

Application filed May 5, 1910. Serial No. 559,629.

To all whom it may concern:

Be it known that I, FRANK C. H. STRASBURGER, a citizen of the United States, residing at Chicago, in the county of Cook and State of Illinois, have invented certain new and useful Improvements in Bottle-Washing Machines, of which the following is a specification.

This invention relates in general to bottle washing machines in which the bottles are carried from one end of the machine to the other on a carrier, and thoroughly cleansed and rinsed during their travel past a series of washing and rinsing devices.

15 It is an object of my invention to provide a single machine of relatively simple construction which will perform all of the soaking, washing and rinsing operations during 20 a single passage of the bottles from one end 25 of the machine to the other, and which will deliver the bottles in a perfectly clean and sweet condition.

Further objects and advantages of the invention will become apparent to those skilled 25 in the art as it is better understood by reference to the following description when taken in connection with the accompanying drawings illustrating a preferred embodiment thereof.

30 Referring to the drawings Figures 1 and 2 constitute a sectional side elevation of a machine embodying my invention, taken on the line 1—1 of Fig. 3. Fig. 3 is a plan of the whole machine. Fig. 4 is a section on the line 4—4 of Fig. 3. Fig. 5 is a section on the line 5—5 of Fig. 3. Fig. 6 is a detailed elevation of my improved washing mechanism. Fig. 7 is a longitudinal section on the line 7—7 of Fig. 6. Fig. 8 is 35 an elevation of my improved washing mechanism showing it in operative position in a bottle. Fig. 9 is a plan of one of the bottle holding sockets. Fig. 10 is a section of a socket showing a bottle in position therein, and Fig. 11 is an enlarged view of the socket shown in Fig. 10.

Referring to the drawings in which like reference characters indicate corresponding parts in the several figures, an endless carrier consisting of a pair of link belts 12 connected by transverse bars or rods 13, arranged to travel around an elliptical frame 14 is intermittently operated by the actuating arms 15 secured upon rock-shafts 16 50 suitably mounted in the side frame of the

machine. The actuating arms 15 are connected at their lower end to a rod 16' adapted to be reciprocated by an eccentric 17 on the shaft 18 suitably mounted on the sides of the frame. The upper ends of the arms 60 are provided with fingers 19 which are urged into engagement with the chain rollers on the carrier by tension springs 19' as the arms are oscillated back and forth to intermittently feed the carrier forward at 65 each actuation of the arms.

The shaft 18 is preferably driven by a worm-gear 20 on a short shaft suitably mounted in the frame and provided with a gear 21 adapted to be driven from a spur-gear 22 secured upon the drive shaft 23 extending longitudinally of the frame and adapted to be operated by a motor 24 or any other preferred form of driving means.

The frame of the machine is inclosed in 75 a casing 26 provided with partitions 27 and 28 which divide the interior of the casing into three compartments. The compartment at the right in Fig. 2 is preferably supplied with an alkaline or acid solution to be employed in the soaking operation: The central compartment preferably contains simply hot water; while the compartment at the left is adapted to receive the cold water 80 which has been employed in the washing 85 and rinsing operations.

The transverse members 13 of the chain carrier are provided with a plurality of sockets 29 shown in detail in Figs. 9, 10 and 11, of suitable shape to support the bottles 90 to be washed in an inverted position. The sockets are preferably made of integral formation and comprise a ring 30 and a contracted neck 31, connected by suitably curved ribs 32. Each socket is provided with an annular flange 33 by means of which it is secured to the transverse bars 13 by rivets 34 or other preferred fastening means.

The carrier with the bottles positioned in the sockets is moved step by step by the actuating arms 15 in the direction of the arrows in Figs. 1 and 2. A plurality of rows 100 of hollow spindles or tubes 35, are supported upon and communicate with a chest 36, (Figs. 3 and 5) and are guided near their upper ends by a suitable guide 37. The chest is mounted to reciprocate in a vertical plane and is guided in its up and down movements by a rod or post 38. A plurality of levers 39 are secured upon the rock- 105 110

shaft 40 extending transversely of the machine, each provided with a weight 41 which may be adjusted longitudinally of the levers to counterbalance the weight of the chest 36, which is supported by arms 42 secured upon the rock-shaft 40. The rock-shaft 40 is actuated to raise and lower the chest and tubes 35 by means of a slotted cam 43 secured upon the shaft 18; which reciprocates a rod 44 by means of a traveler 45 secured upon the rod 44 and adapted to travel in the slot in the cam. The rod 44 is connected at 46 to the lower end of an arm 47 secured upon the shaft 40. The chest is supplied with the soaking solution from the compartment by means of a rotary pump 48 which communicates with the compartment through intakes 49 and with the chest through a flexible connection 50.

20 The mechanism is so timed that as the bottles are brought to rest over the tubes 35, the tubes are raised into the bottles, thus spraying the soaking solution over the interior of the bottles, and also spraying the exterior of the bottles before and after the tubes enter the bottles. I have shown four rows or series of tubes, and when this number is employed, it will be evident that each bottle receives four applications of the soaking solution both inside and outside the bottle. It will be obvious, however, that the number of series of tubes may be increased or diminished, as desired.

As the bottles are carried along from the soaking chamber, they pass into the washing chamber and are brought to rest over the tubes 51 carried by a chest 52 and guided by a suitable guide 53 similar to the soaking tubes and chest. The chest 52 is also adapted to be reciprocated in a vertical plane and guided by a post or rod 54. A plurality of weighted levers 55 are secured upon a rock-shaft 56 which supports the chest 52 by means of the arms 57. A connecting rod 58 connects the arm 47 with the arm 59 secured upon the rock-shaft 56, so that the tubes 35 and 51 are reciprocated simultaneously. Water from the washing compartment is supplied to the tubes 51 by a suitable pump 60 through a flexible connection 61, the water being supplied to the pump through suitable intakes 62. The operation of the washing mechanism is similar to the operation of the soaking mechanism, and while any preferred washing liquid may be employed, I have found very satisfactory results are effected by the use of hot water.

60 After the bottles have passed through the soaking and washing operations, there may still remain in the bottles some foreign matter which sticks tightly to the interior thereof, and in order to remove this matter, the bottles are subjected to a further washing operation in the left-hand compartment of

the machine. In order to effect this washing operation I have provided a plurality of rows of hollow spindles 63 suitably mounted in bearings 64 carried upon a chest 65 with which the lower ends of the tubes communicate, the upper ends being in suitable guides 66. Referring particularly to Figs. 6 to 8 inclusive, each tube is provided with a longitudinal slot near its upper end into which there is fitted a sheet of rubber 67 or other suitable flexible material which can be inserted into the mouth of a bottle and which comprises the washing member. The flexible sheet is maintained in position by a cap 68 screwed over the end of the spindle. An angularly disposed channel 69 communicates with the bore of the spindle and provides a discharge passage through which the liquid from the chest 65 is sprayed into the bottle.

85 The liquid may be supplied to the chest 65 from the city water main or any other suitable source of supply. The spindles are driven through gears 70 secured thereon, one of which meshes with a gear 71 on a vertical shaft 72 which carries a bevel-gear 73 adapted to mesh with and be driven by bevel-gear 74 on the horizontal shaft 75 carried in suitable bearings 76, 77 and 78, and having at its outer end a bevel-gear 79. A casing 80 incloses a vertical shaft 81 carrying a bevel-gear 82 adapted to drive the gear 79 and also a bevel-gear 83 adapted to mesh with and be driven by a bevel-gear 84 secured upon the main drive shaft 23. Any other suitable driving connection may be employed to impart a rotary motion to the spindles, if preferred. The chest 65 is also adapted to be reciprocated in a vertical plane by means of arms 86 carrying the chest and secured upon a rock-shaft 87 which is actuated simultaneously with rock-shafts 56 and 40 through a link 88 and an arm 89 secured on the shaft. Suitable weighted levers 90 counterbalance the weight of the chest and spindles.

105 When the spindles are raised the flexible cleaning members 67 are forced into the bottles positioned in alignment therewith, and engagement of the cleaning members with the bottom and side walls of the bottles upon rotation of the spindles, will, in conjunction with the jet of water sprayed from the opening 69, remove any foreign matter which may still remain in the bottles.

115 Since the machine is adapted to be used for cleaning bottles of various sizes such as quarts, pints or splits, and since the height to which the spindles are raised at each reciprocation remains constant, it will be evident that the bottles will be raised by the spindles out of the sockets. In order that the bottles will not rotate with the spindles but will be held so that the cleaner will op-

erate inside, I have provided holding means disposed in alignment with the spindles and above the bottom of the bottles. The holding means comprises essentially a plurality 5 of square bars or shafts 91 carried by a supporting frame 92, and capable of limited longitudinal movement in bearings 92' in the top of the casing 26, as shown in Fig. 1. The bars 91 are provided at their lower ends 10 with holding members 93 adapted to engage with the bottom of the bottles as they are raised by the spindles. It will be evident that when small sized bottles are being washed the washing spindles will engage 15 the bottoms of the bottles sooner than they would the larger sized bottles, and in order to prevent the smaller bottles from rotating with the spindles when they are lifted from their sockets I have made the bottle holding mechanism vertically adjustable whereby it may be adjusted to bottles of varying heights.

The adjusting mechanism comprises a rock-shaft 94 extending transversely of the 20 machine and provided at either end with arms 95 connected to the supporting frame 92 by links 96, as shown in Figs. 1 and 4. A handle 97 is secured to one end of the rock-shaft and is adapted to engage with a 25 holding segment 98 secured upon the casing of the machine. It will be evident that by means of the handle 97 the holding members 93 may be adjusted to any desired position.

After the washing operations the bottles 30 pass over a spray chest 99 (Fig. 1), provided with openings in its top through which the water sprays over and into the bottles to thoroughly rinse and cleanse them. Water is supplied to the chest 99 from the 35 chest 65 through a suitable connection 100. The bottles are further rinsed by means of one or more pipes 101 extending through the casing and provided with spray openings through which the water is sprayed 40 over the bottles.

Each bottle in its passage through the machine, is subjected to several actions of a soaking solution, then to several actions of hot water, subsequently to a jet of water in 45 conjunction with the washing member which rotates within the bottle and loosens and removes any matter which may be sticking thereto, while the bottle is held against rotation with the washing member, and eventually 50 each bottle is thoroughly rinsed both inside and outside by sprays and jets of cold water. The machine embodying my invention performs during a single passage of the bottles through the machine, a complete 55 cleansing and purifying of the bottles, thereby expediting the washing operation and greatly reducing the cost of labor of the cleansing operations.

While I have shown and described a preferred embodiment of my invention, it will

be evident that various minor mechanical changes may be resorted to without departing from the spirit of the invention or sacrificing any of the material advantages thereof.

What I claim is:

1. In a bottle washing machine, the combination of a casing, a track extending longitudinally of the casing in the upper portion thereof, said casing having openings in each 70 end wall adjacent to said track, sprocket wheels mounted at each end of the casing, an endless carrier trained over said sprocket wheels, one lap of said carrier extending through the casing above the track and the other lap extending beneath the casing, vertical partitions in the casing below the track dividing the casing into a series of compartments, vertically movable bottle washing devices in the respective compartments, 75 an operating lever connected with the bottle washing devices in each compartment, a counter-weight mounted on each lever, a driving shaft, a cam thereon, means connecting said cam with each of said levers whereby the levers are simultaneously operated to raise and lower said bottle washing devices, a second cam on said shaft, a plurality of carrier operating levers, dogs carried by 80 said levers in position to engage said carrier, and connections between said levers and said second cam whereby said levers are simultaneously operated, in alternation with the levers for raising and lowering the bottle washing devices, to intermittently advance the carrier when the bottle washing devices are in lowered position.

2. In a bottle washing machine, the combination of a casing having openings in opposite side walls, an endless carrier movably disposed through said openings and passing beneath said casing and provided with a plurality of bottle receiving sockets, partitions in said casing and beneath said carrier dividing said casing into a series of compartments, vertically movable bottle washing devices in the respective compartments, an operating lever for the bottle washing devices in each compartment, a driving shaft, means for connecting said driving shaft to said levers to raise the bottle washing devices through the sockets and into bottles on the carrier periodically and simultaneously from the various compartments, and means connecting said carrier with said shaft for actuating the carrier intermediate the actuation of said bottle washing devices.

3. In a bottle washing machine, the combination of a casing having openings in opposite sides, sprocket wheels mounted on the casing beyond said openings, an endless carrier trained through said openings over said sprocket wheels and beneath said casing and provided with a plurality of bottle receiv- 125

ing sockets, partitions located beneath said carrier and dividing the casing into a series of compartments, bottle washing devices located in each compartment, a shaft, connections between said shaft and carrier, and connections between said shaft and bottle washing devices for alternately elevating said bottle washing devices from the com-

partments through the sockets and into bottles on the carrier and for advancing the carrier after each operation of the bottle washing devices.

FRANK C. H. STRASBURGER.
